UNITED STATES PATENT OFFICE.

OSWALD C. STACKHOUSE, OF BROOKLYN, NEW YORK.

DESIGN FOR A NEBULIZER.

43,971.

Specification for Design.

Patented May 6, 1913.

Application filed February 15, 1913. Serial No. 748,739. Term of patent 7 years.

To all whom it may concern:

Be it known that I, OSWALD C. STACKHOUSE, a citizen of the United States, residing in Brooklyn, in the county of Kings and State of New York, have invented a new, original, and ornamental Design for Nebulizers, of which the following is a specification, reference being had to the accompanying drawings, forming part thereof.

The figure is a perspective view of a nebulizer showing my new design.

I claim:—

The ornamental design for a nebulizer as shown.

OSWALD C. STACKHOUSE.

Witnesses:

WARREN E. WILLIS,
ESTHER GENDEL.
